(57) CLAIM

The ornamental design for a display case for bottles, as shown and described.

DESCRIPTION

FIG. 1 is a perspective view of a display case for bottles showing my new design;

FIG. 2 is a front view of a display case for bottles showing my new design; and,

FIG. 3 is a left side view of a display case for bottles showing my new design.

Elements shown in broken lines in FIGS. 1-3 do not form part of the design for which protection is sought.

1 Claim, 1 Drawing Sheet

FIG. 1
